UNITED STATES PATENT OFFICE.

CHARLES CLEMENTS, OF BOSTON, MASSACHUSETTS.

METHOD OF PRODUCING PHOTOGRAPHIC REPRESENTATIONS OF STRUCTURAL DESIGNS.

No. 927,116.

Specification of Letters Patent.

Patented July 6, 1909.

Application filed March 5, 1909. Serial No. 481,305.

To all whom it may concern:

Be it known that I, CHARLES CLEMENTS, a citizen of the United States, and resident of Boston, in the county of Suffolk and State of Massachusetts, have invented new and useful Improvements in Methods of Producing Photographic Representations of Structural Designs, of which the following is a specification.

10 My invention consists in an improved method of producing photographic representations of structural designs, by the aid of which such representations may be made to present to the eye vividly the prominent features of the structures represented, in verisimilitude thereto not only in the form but also in contrasts of texture, finish or other superficial characteristics.

In Letters Patent of the United States, 20 No. 910,990, granted to me January 26, 1909, there is shown and described a method of producing photographic representations of structural designs, by the aid of which the main object of the invention herein described may be obtained, but which is not so well adapted to the production of photographic representations involving elaborate details as is the method herein set forth.

My new and improved method is in one 30 aspect an alternative or substitute for that set forth in my said patent, while in another aspect it is an improvement thereon, as it furnishes facilities for representing elaborations and details of design not possessed by my said patented method.

In submitting designs for ornamental structures, especially where, as is usually the case, the design submitted is very much smaller than the structure is intended to be, 40 it is difficult and I believe impossible, by means of the usual devices heretofore employed to convey to the average mind an adequate idea of the texture, grain or other superficial characteristics of the materials 45 which are to enter into the finished structure, particularly in respect to salient portions of a design. The individual peculiarities of his materials are among the most effective resources of the designer and while he by constant contact and experience with the materials of his craft may be well able to picture to himself the resultant effect of a design 50 when wrought into its ultimate materials, it is unusual for the person to whom the design 55 is submitted, and whose approval or disap-

roval may be final, to stimulate his imagination to the point of adequately visualizing what may be the most essential elements in the design. It might be assumed by those unfamiliar with this subject that a photograph from an actual structure would convey better than any other vehicle an adequate idea of the structure itself; this however, is by no means true, as my own experience and that of others has often demonstrated. The 60 photograph almost invariably shows the structure very much reduced from its natural size so that the essential peculiarities and contrasts of grain, texture, marking, color etc. which render the actual object distinctive and pleasing are for the most part, if not wholly, suppressed and obliterated by the process of photographic reproduction. It is obviously impossible to furnish photographs in full size of many objects of art and architecture, and it is also obviously impossible by any means heretofore usually employed to reproduce with fidelity, in the design of a structure which exists only in contemplation, those features of peculiar texture, grain etc. 70 which are peculiar to the materials intended to be employed.

By my invention herein described there may be produced an unlimited variety of composite objects for photographic reproduction which shall present to the eye of the observer the salient features selected by the designer, in their natural appearance; and the natural appearance will be accentuated in the design as a whole by reason of the fact 85 that, while the design will be drawn to a reduced scale, those salient portions which the designer wishes to emphasize will have their natural details exaggerated in relation to the design as a whole and thus stand prominently 90 forth, conveying to the person for whom the design is made a vivid and therefore adequate idea of the appearance which the structure will assume when completed.

While the method described in my said 100 Patent No. 910,990 is adequate for the reproduction of simple designs, the difficulty of its application increases with the elaboration or complexity of designs, and, while my method herein described may be employed to produce representations of simple designs, its 105 range of practical employment is much greater than that of my said patented process.

In the drawings hereto annexed, which 110

2
illustrate my herein described invention, there is shown a composite surface, representing a monument. In preparing this composite surface, or object to be photographed, I take for the background surface a plain sheet, A, preferably card board or bristol board. Having previously made sheets imprinted with photographic representations of actual material surfaces, hav-

5 ing various qualities, of light, color and texture, I employ these for the formation of the picture or design applied to the background A.

If the design is to be of a monument, as shown in the drawing, I take a sheet, photographically representing and preferably in full size, the surface of cut and axed granite, and cut out of this sheet, B, a piece having the contour of the design. Then I take another sheet, on which is photographically 15 represented, in full size, preferably, the surface of the same granite when polished, and cut from this pieces properly shaped to comport with the design outlined by the sheet D. These pieces are represented at C, C' and C²; 20 the ornamentation and elaboration suggested at C² are easily produced. I secure, as by pasting, the sheet B in proper posture on the background A, and then place the pieces C, C', C² upon and secure them to the 25 piece B, in the manner illustrated. Fine lines may then be drawn upon the piece B, to indicate the junctures of surfaces, and, if desired, an aspect of solidity may be produced by shading portions of the applied pieces, as 30 at B', B². The outline b, b of the design will be in most instances sufficiently contrasted 35 with the background A.

Having thus prepared a composite object, I photograph it; and from the photographic 40 plate reproductions can be made by the usual processes.

While I have shown by way of illustration, a composite object for photographic reproduction in which natural stone or a facsimile 45 thereof is employed, the same idea may be carried out according to this invention by using natural woods, textile fabrics, ornamental paper, in short what you will; according to the nature of the structure which 50 the design as a whole represents. The fact that the natural object which forms part of the composite presents its peculiar features of surface to the camera in full size exaggerates those qualities which this material 55 would eventually contribute to the structure represented and thus emphasizes to the eye of the observer the effect which the material selected is intended to produce.

What I claim and desire to secure by Letters Patent is:

1. The method of producing photographic reproductions of structural designs which consists in superposing upon a background surface sheets previously prepared by having 65 imprinted thereon photographic representa-

tions of several actual surfaces of such materials as are to be used in the finished structure represented by the design, the details of such photographic representations being of exaggerated proportions in relation to the 70 dimensions of the design, and finally photographing the composite surface so formed.

2. The method of producing photographic representations of structural designs which consists in laying upon a background surface 75 first a sheet printed photographically with a representation of the actual material surface which the main body of the designed structure is to present, the said final sheet being cut to an outline to represent the main outline of the design, thereafter laying over said first sheet, and within the marginal limits of the design, other sheet material, photographically representing an actual material surface in contrast to the first sheet, and cut to outlines in conformity with the design of the 80 structure; the photographic details of said sheets being of exaggerated proportions in relation to the dimensions of the design, and finally photographing the complete surface 85 so formed.

3. The method of producing photographic representations of structural designs which consists in superposing upon a background surface sheets previously prepared by having 90 imprinted thereon photographic representations of several actual surfaces of such materials as are to be used in the finished structure represented by the design, the details of such photographic representations being of 95 exaggerated proportions in relation to the dimensions of the design, shading selected portions of the sheets thus superposed upon the background, to produce the semblance of 100 solidity, and finally photographing the composite surface thus formed.

4. The method of reproducing photographic representations of structural designs which consists in laying upon a background surface first a sheet printed photographically 110 with a representation of the actual material surface which the main body of the designed structure is to present, the said first sheet being cut to an outline to represent the main outline of the design, thereafter laying over 115 said first sheet, and within the marginal limits of the design, other sheet material, photographically representing an actual material surface in contrast with the first sheet, and cut to outlines in conformity with the design 120 of the structure, the photographic details of said sheets being of exaggerated proportions in relation to the dimensions of the design, then shading selected portions of the sheets 125 thus superposed upon the background surface, to produce the semblance of solidity, and finally photographing the composite surface thus formed.

5. The method of producing photographic representations of structural designs which 130

consists in forming upon a background surface a representation of the main body of the structure which the design is to represent, approximating to the actual appearance of 5 the surface of said main body, then superposing thereon, and within the limits of the outline thereof, sheet material cut to represent component contrasting portions of the design, said sheet material being imprinted 10 with a photographic representation of actual surfaces of materials such as are to be used in the finished structure represented by the

design, the details of such photographic representations being of exaggerated proportions in relation to the dimensions of the 15 design, and finally photographing the composite surface thus formed.

Signed by me at Boston, Massachusetts this first day of March 1909.

CHARLES CLEMENTS.
